UNITED STATES PATENT OFFICE.

ERICH STROHBACH, OF VIENNA, AUSTRIA.

FILM-FIRE EXTINGUISHER.

1,392,233.

Specification of Letters Patent. Patented Sept. 27, 1921.

Application filed August 1, 1914. Serial No. 854,600.

(GRANTED UNDER THE PROVISIONS OF THE ACT OF MARCH 3, 1921, 41 STAT. L., 1313.)

To all whom it may concern:

Be it known that I, ERICH STROHBACH, a subject of the Emperor of Austria, and a resident of Vienna, in the Empire of Austria,

whose post-office address is Vienna, XXI. Leopoldau, have invented a Film-Fire Extinguisher, of which the following is a specification.

This invention relates to and has for its object to devise an improved means for preventing flames from spreading along celluloid films, strips, filaments or the like which have caught fire.

Celluloid in the form of strips is used on a large scale for the manufacture of films. Numerous experiments have been made with the object of eliminating the risks arising from such films when they catch fire. It has already been discovered that celluloid films, strips, filaments or the like which have caught fire may be extinguished with comparative ease, if suitable means are provided for removing as rapidly as possible the resulting heat, so that the temperature sinks below the ignition point of celluloid. This may be done by employing metallic surfaces *e. g.* in the form of metal plates between which the film, the strip or the filament is allowed to travel.

This invention substantially consists in the combination of the aforescribed heat-removing method with the starting of a chemical reaction which liberates from suitable substances (by supplying heat thereto) combustion-preventing gases. All organic and inorganic salts, which on being heated give off carbonic acid, ammonia or aqueous vapor such as sodium bicarbonate, carbonate of ammonium or powdered alum contain-

ing water of crystallization, are such substances which may be used for the above purpose. In order to facilitate the action of these gases on the film or filament which has caught fire, the metal plates may be suitably perforated, or sieve-like structures may be employed. According to this invention therefore not only the resulting heat is removed from the film which has caught fire, by the metal surrounding the said film but at the time the salts which are now heated,

which therefore give off carbonic acid, ammonia or aqueous vapor, deprive the film of the oxygen which is necessary for combustion.

A suitable device for carrying the method into practice consists of a closed narrow channel, and vessels containing substances which liberate combustion-preventing gases. The sides of the vessels facing the channel may be closed by perforated plates permitting the gases to escape into the channel. By such arrangement the gases generated in consequence of the heating of the said carriers emanate only into the channel and acting exclusively in the same.

One embodiment of such a device is shown, by way of example, in the accompanying drawings.

In said drawings, Figure 1 is a side view of the device, partly in cross-section and partly in elevation.

Fig. 2 is a perspective view of the device, parts being broken away.

1 is a guiding frame forming a narrow guiding interstice for the strip of celluloid (film 2 or the like). This guiding frame is preferably fixed to the film drum, in such a manner, that the film enters the guiding frame immediately after leaving the drum. With the embodiment shown, the frame 1 carries boxes 3, the bottoms of the said boxes being formed by sieves 4 or the like between which the film passes. The boxes 3, which preferably in order to permit of renewal in case of emergency, are detachably fixed upon the guiding frame, serve as containers of a substance generating gases which prevent combustion.

By means of the sieves or other perforated bodies facing the film, heat is absorbed from the film if the film happens to burn and thereby the gas-generating substances are heated so that the generation of such combustion-preventing gases is set up. The said gases being permitted to escape only by the said narrow channel, the flame-extinguishing action of these gases is effective under all circumstances and thereby the fire suppressed.

I prefer to make the upper box larger

than the lower one because the heat action is stronger upon the upper box than upon the lower box.

It is also preferable to provide such an arrangement as well upon the drum, wherefrom the film uncoils itself as upon the drum serving for upwinding of the uncoiled film, whereby the spreading of the fire is prevented upon each drum.

10 Having now particularly described and ascertained the nature of my said invention and in what manner the same is to be performed, I declare that what I claim is:—

15 1. An apparatus for use in preventing flames from spreading along celluloid films or the like, comprising a substance adapted to liberate inert gases upon being heated by the combustion of a film to suppress combustion, and a good heat conductor at one 20 side of said substance, so that the apparatus may be located with the heat conductor between said substance and the film, said conductor being adapted to extract heat from said film and transmit it to said substance.

25 2. An apparatus for use in preventing flames from spreading along celluloid films or the like, comprising a substance adapted to liberate inert gas upon being heated by the combustion of a film to suppress combustion, a perforated metal plate at one side of 30 said substance, so that the apparatus may be located with the perforated plate between said substance and said film, said plate being adapted to extract heat from

said film and transmit it to said substance, 35 and allow the liberated gases to pass through said perforations into the path of said film.

3. An apparatus for use in preventing flames from spreading along celluloid films or the like, comprising a guideway through 40 which the film is adapted to pass, said guideway having boxes on either side thereof, said boxes having perforated walls facing said guideway, and said boxes containing a substance adapted to liberate inert gases upon 45 being heated by the combustion of said film, said gases being adapted to pass through said perforated walls into said passageway to suppress combustion of said film.

4. An apparatus for use in preventing 50 flames from spreading along celluloid films or the like, comprising a guideway through which the film is adapted to pass, said guideway having detachable boxes on either side thereof, said boxes having perforated walls 55 facing said guideway, and said boxes containing a substance adapted to liberate inert gases upon being heated by the combustion of said film, said gases being adapted to pass through said perforated walls into said passageway to suppress combustion of said film.

In witness whereof, I have hereunto signed my name in the presence of two subscribing witnesses.

ERICH STROHBACH.
